UNITED STATES PATENT OFFICE.

MARTIN W. CARR, OF SOMERVILLE, MASSACHUSETTS.

DESIGN FOR A VASE.

SPECIFICATION forming part of Design No. 17,627, dated August 16, 1887.

Application filed May 12, 1887. Serial No. 238,000. Term of patent 3½ years.

To all whom it may concern:

Be it known that I, MARTIN W. CARR, a citizen of the United States, residing at Somerville, in the county of Middlesex, State of Massachusetts, have invented and produced a new and original Design for Vases or Bouquet-Holders, of which the following is a full, clear, and exact description, reference being had to the accompanying drawing, forming a part of this specification, in which the figure is an isometrical perspective view, representing my newly-designed vase or bouquet-holder.

The leading features of my design consist in the holder A, base B, and standard x.

The holder is in imitation of a flower of the tiger-lily plant, represented as standing vertically over the base B, which is in imitation of a broad leaf having a mid-rib and veins. The handle m of the vase is in imitation of the petiole or stem of the leaf coiled, as shown. The standard x is in imitation of the stalk of the flower, said stalk being represented as having its upper end extending freely above said leaf and passing into the base of said flower, and 25 its lower portion curved and in contact with the surface of the leaf in such a manner that the end of the stalk passes over the base of the mid-rib y and curves under the blade of the leaf. The leaf B is shown as on a circular support or pedestal, C, which represents the foot 30 of the vase.

Having thus explained my design, what I claim is—

The design for a vase or bouquet-holder herein shown and described, consisting of a 35 base in imitation of a broad leaf having its surface in representation of a mid-rib and veins, a pedestal underneath said leaf, a holder in imitation of the flower of the tiger-lily plant, a support in imitation of the stalk of said 40 flower, said stalk resting on said leaf, its upper end extending freely above said leaf and passing into the base of said flower, and a handle in imitation of the coiled petiole or stem of the leaf.
